INTERVALOMETER

Harry R. Habig, Dayton, Ohio

Application July 9, 1943, Serial No. 494,027

17 Claims. (Cl. 161—1)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to intervalometers, the same being instruments for actuating mechanical or electrical devices at preselected intervals.

There are many situations where a device of this character is applicable, such, for instance, as for actuating a camera shutter at definite intervals in aerial mapping, or for periodical operation of bomb release equipment in aerial warfare.

An object of the invention is to provide a device of this character which is of light weight and small dimensions and suitable for mounting on the instrument panel of an aircraft.

Another object is to provide a device of this kind which is extremely accurate in repeatedly operating its actuating mechanism at the exact interval selected.

Another object is to provide an instrument of this class having starting means whereby the first one of the intervals between actuations is of exactly the same length as those following.

Other objects and advantages will be recognized as the invention is further described and reference is made to the drawings, wherein,

Fig. 1 is a schematic view of the device, particularly showing the electrical connections between the several elements.

Fig. 2 is an elevational view of the device, parts being in section.

In the drawings, a framework 10, intermediate its ends, carries an electric motor 12 arranged to drive a rotatable shaft 14. The rearward end of shaft 14 carries a centrifugal governor 16 for holding the motor to a uniform speed.

The governor comprises a disc 18 fast on the shaft 14 with arms 20 extending rearwardly to support a thin flat spring 22 with weights 24 secured to the forward side of the spring at its ends, as shown. An electrical contact member 26 is secured to the rearward face of the spring 22 concentric with the axis of shaft 14 for unitary rotation therewith.

A nonrotatable contact member 28 is concentrically positioned for engagement with the contact member 26. Contact member 28 is carried on the forward end of a screw 30 which is threaded in the bracket 32, whereby the contact member 28 may be adjusted toward or away from the contact member 26 for raising or lowering the speed of the motor 12. A brush 33 rides on the front face of the disc 18 to bring current to the

rotating part of the governor. A resistance 35 cuts around the governor when the contacts 26 and 28 are separated by an overspeed condition of the governor.

5 Fast on the motor shaft 14 at its forward end, is a pinion 34. Pinion 34 is in mesh with a gear 36, which is freely rotatable on a countershaft 38. A pinion 40 is fastened to the gear 36, but is free on the countershaft whereby they rotate 10 together as a gear-and-pinion assembly. Four more gear-and-pinion assemblies 36-40 are contained in the gear set, two assemblies being freely rotatable on the countershaft 38 and two being freely rotatable on the clutch shaft 42. A gear 15 36, which does not have a pinion 40 attached, is freely rotatable on the clutch shaft 42 at the outer end of the group.

An electromagnetic clutch 44 is provided for dryably securing the outer gear 36 to the clutch 20 shaft 42, whereby the motor 12 will drive the clutch shaft 42 at a greatly reduced speed.

The clutch 44 includes a coil 46 which surrounds a core 48 within a coil housing 50. A disc 52 is integral with, or otherwise fastened to, the 25 clutch shaft 42. The coil 46, core 48, and housing 50 may be collectively referred to as the clutch engaging electromagnet. An antifriction bearing 54 holds the front face of the disc 52 slightly away from the rear face of the core 48 and at the same time holds the rear face of the disc 52 slightly beyond the rear face of the housing 50. By this arrangement, when the coil 46 is energized, the outer gear 36, acting as an armature, is drawn to the face of the disc 52 but cannot make contact with the housing 50 nor can the disc 52 rub the end of the core 48. A torsion spring 53, with one end fastened to the core 48 and the other end to the clutch shaft 42, opposes 30 rotation of the shaft by the motor 12.

The motor 12, the governor 16, and the clutch 44 occupy the middle portion of the framework 10 and are all in axial alignment, one with the other. Additional units are a mechanically operated switch mechanism 55 at the right hand or front end of the framework, and another switch mechanism 57, which is operated in part mechanically and in part electrically at the left hand or rear end of the framework. These switch 45 mechanisms also have axes coincident with the motor, governor, and clutch axis. It should be noted, however, that in the schematic view, Fig. 1, the axes of the two switch units have been 50 swung around ninety degrees to better show the electrical circuits. In Fig. 2, however, the true 55

arrangement is shown, the motor 12, governor 16, clutch 44, and the two switch units 55 and 57, all being in axial alignment.

The mechanically operated switch mechanism 55 is contained within a control knob 56, by which the interval between successive actuations is selected. Control knob 56 is hollow, and is internally threaded as at 58 to fit over external threads on the clutch housing 50. The threads 58 not only provide rotative bearing for the knob, but prevent its coming off after assembling.

When the control knob 56 is assembled on the end of the clutch housing, as shown in Fig. 2, space is left in the outer end of the knob for two switches 60 and 62, and the switch operating arm 64, which is also the interval measuring arm (see Fig. 1).

Switch 60, which may conveniently be called the actuator switch, is provided for closing a circuit through the coil 65 of an actuating mechanism, which may be either directly attached to a camera shutter or to a relay when a mechanism requiring considerable force is to be actuated. The coil 65 and its core 63 may collectively be referred to as the actuator electromagnet, and while it may be built in as part of this invention, it may preferably be a part of the mechanism which is to be actuated, in which case terminals only may be provided on the intervalometer for connecting the coil 65.

Switch 62 is provided for closing a circuit to a coil 67, which is wound on a core 61 in a housing 71. The coil 67, core 61 and housing 71 may collectively be referred to as the clutch disengaging electromagnet, since this magnet opens a switch 69 for breaking the circuit through the coil 46 of the clutch 44 and thereby disengages the clutch. The switches 62 and 69 may conveniently be referred to as the first and second clutch-disengaging switches, respectively.

Switch 60 includes a movable switch arm 66 hinged on a stud 68 extending forward from the front face of the clutch housing 50, and having attached thereto an operating lug 70 and a contact member 72. It includes, also, a second switch arm 74, hinged on a stud 76, also extending forward from the front face of the clutch housing 50, and having a contact member 78 positioned for engagement with the contact member 72.

Switch 62 employs the arm 74 in common with switch 60, the movable contact member 80 of switch 62 being fast to the arm 74 opposite the contact member 78. A stationary contact member 82 is carried on a bracket 84 fixed to the front of the clutch housing 50. A screw 86 in a bent part of the arm 74 is provided for adjusting the gap between the contact members 80 and 82.

Springs 88 and 90 yieldably hold the switches 60 and 62 in their full open position. A stop 92 limits movement of the switch arm 66.

The operating arm 64, which may also be referred to as the interval measuring means, is carried on an extended end of the clutch shaft 42 whereby it is rotated clockwise by the motor when the clutch 44 engages, and anti-clockwise by the torsion spring 53 when the clutch releases. A stop 94 is provided to arrest anti-clockwise rotation of the operating arm 64 by the spring 53. Stop 94 is fastened to the inside of the control knob 56 near the closed end and rotates with it. The extent, therefore, that the control knob 56 is manually rotated anti-clockwise, determines the time interval which the switch operating arm 64 consumes from the time that clutch engagement

takes it away from the stop 94 until it reaches the lug 70, operates the switch 62 to release the clutch, and is returned by the spring 53 to the stop 94. A screw 96 is provided for making minor adjustments to correlate the stop 94 with the graduations 98 on the knob 56. An index pointer 100 cooperates with the graduations 98 to visibly indicate the position of the stop 94 and, therefore, the interval which will elapse between 10 actuations. The stop 94 thus serves as a gauge which may be adjusted to vary the starting point of the interval.

Circumferentially spaced around the inner periphery of the control knob 56 are a series of 15 detent notches 102 which correspond in spacing to the graduations 98. The forward end of a long rod 104 is supported in a slot 106 in the framework whereby this end of the rod may have slight movement toward or away from the clutch shaft 42. A light spring 108 yieldably holds the rod 104 in that one of the notches to which the control knob 56 has been turned. The notches 102, rod 104, slot 106 and spring 108 constitute a 20 detent mechanism which securely holds the control knob 56 with the selected one of the graduations 98 at the index pointer 100.

In addition to its function in the detent mechanism, the rod 104 is operable endwise for opening the motor switch 110 to stop the motor 12 whenever the control knob is turned beyond the 25 maximum graduation.

A cam 112 fast on the inside of the control knob 56 near the open end, is so placed that just as the knob passes the maximum graduation, the cam pushes the rod to the left against the adjusting screw 114, whereby the switch 110 is opened and the motor stops. The left end of the rod 104 has bearing in the framework at 116. A spring 118, acting against this bearing and against a shoulder 120 on the rod, 30 moves the rod to the right whenever the control knob is turned beyond the maximum graduation. The motor 12 is therefore operative in any position of the control knob except positions beyond the maximum.

The switch mechanism 57 at the left or rear end of the framework 10 includes a switch arm 122 hinged on a stud 124 which extends rearward from an insulating disc 126, the disc being part of the framework of the device. The switch 69 has one contact member 128 fast on the arm 122 and another contact member 130 secured to the disc 126. The switch 69 is normally closed as shown, but will momentarily be drawn to an open state when the switch 62 at the opposite end of the 35 device closes and directs current to the coil 67.

The closing of the switch 62 by clockwise rotation of the arm 64 opens the switch 69 and disengages the clutch 44, whereupon the torsion spring 53 starts anti-clockwise rotation of the arm 64. A very slight anticlockwise rotation of the arm 64, however, will open the switch 62 and reengage the clutch before the arm has had time to reach the stop 94. Some delaying means must therefore be provided to hold the switch 69 open until the arm 64 has had time to return to the stop 94.

The mechanism provided for delaying reengagement of the clutch 44 until the arm 64 has had time to return to the stop 94 includes a pinion 132 fast on a shaft 134, the pinion being in mesh with one of the gears 36. A cam 136 is free on the shaft 134 except that it is frictionally driven by the shaft by means of a spring 138 which presses the cam between the washers 140 and 142. Thus, while the shaft rotates continuously in the direction of the arrow 144, the cam is

kept from rotating by the free end of the switch arm 122 until the coil 67 becomes energized by closing of the switch 62, whereupon the switch 69 opens and the cam is released for one complete return. The time taken by the cam 142 to make a complete revolution should be somewhat greater than it would take the torsion spring 53 to rotate the arm 64 anti-clockwise through one complete revolution.

The schematic view, Fig. 1, shows the electrical connections. The plus side of a source of electrical energy 146 is connected to one side of the motor 12, the other side of the motor being connected to the minus side of the current source, either through the governor 16 and motor switch 110, or through the resistance 35 and motor switch 110 when the governor contacts 26 and 28 separate from overspeed.

The plus side of the source 146 is also connected to one end of the clutch coil 46, the other end of the coil being connected to the minus side of the source through a manual switch 148, the electrically operated switch 69, and the motor switch 110.

The plus side of the source 146 is also connected to the hinge post 76 of the switch arm 74 which is common to the two switches 60 and 62, the current, upon closing of the switch 60 being returned to the minus side of the source through the actuating coil 65, whereas the current, upon closing of the switch 62, is returned to the minus side of the source through the coil 67 and motor switch 110.

The operation of the device is substantially as follows:

With the manual switch 148 open, the control knob may be turned clockwise to the desired interval, whereby the pointer 100 will point to the graduation selected. This allows the rod 104 to move to the right and close the motor switch 110, whereupon the motor starts rotating.

If, for example, the desired interval is ten seconds, the knob will be turned to the position shown in Fig. 1. The stop 94 moves with the knob, and the arm 64 is caused by the torsion spring 53 to follow the stop. Only the circuit through the motor 12 is as yet closed.

The manual switch 148 is now closed, thereby completing a circuit through the clutch coil 46, by way of switches 69 and 110, which engages the clutch. The arm 64 therefore starts rotating clockwise away from the stop 94. When the arm strikes the lug 10, it first closes the switch 60 which completes a circuit through the actuating coil 65, then continues on and closes the switch 62, which completes a circuit through the coil 67 and motor switch 110, which magnetically opens the switch 69 which breaks the circuit through the clutch coil 46, whereupon the arm 64 is started back toward the stop 94 by the torsion spring 53.

As soon, however, as the arm 64 moves slightly backward toward the stop 94, the switch 62 opens, which deenergizes coil 67, and would, except for the cam 136, allow substantially instantaneous closing of the switch 69 for clutch reengagement and clockwise rotation of the arm 64. The cam 136, however, delays the closing of the switch 69 until the arm 64 gets back to the stop 94 before the clutch can be again reengaged for beginning a new interval. Energization of the coil 65 and consequent actuation of the camera shutter or other device is thus repeated at the interval to which the knob has been set until the knob is

returned to a position beyond the maximum for stopping the motor or to some other position for a different period of actuation.

With a given motor speed and a given speed reduction through the gearset, the graduations 88 on the control knob 56 are spaced for one second intervals. The instrument may therefore be set for intervals of one second to sixty seconds by means of the control knob without changing the motor speed. It will be apparent, however, that the motor speed may be doubled and the value of the graduations taken as half seconds, or the motor speed may be halved and the value of the graduations taken as two seconds. The 15 detent notches 102 may be cut to correspond to smaller graduations if desired.

It is noted that while the manual switch 148 is provided as an added convenience, it may be dispensed with by permanently closing the circuit which it is intended to open. When this is done, however, oscillation of the arm 64 begins as soon as the control knob is turned clockwise away from the off position, and continues to oscillate, and consequently to actuate the electromagnet 63-65, while the desired interval is being selected.

Having thus described my invention, what I claim is:

1. An instrument for electrically energizing the coil of an actuating device at selected accurately spaced intervals, which comprises, in combination, an electric motor, a governor for maintaining said motor at a uniform speed, means for adjusting said governor for different motor speeds, a switch for starting and stopping said motor, a gearset drivably connected to said motor, a clutch shaft, a clutch engageable for drivably connecting said clutch shaft to the driven gear of said gearset, a clutch-engaging electromagnet, a switch operating arm extending radially from said clutch shaft operative to be turned forward by said clutch shaft when said clutch engages, a torsion spring for turning said arm backward when said clutch disengages, a graduated control knob rotatable forward from an off position, a stop carried on said control knob circumferentially movable by rotation of said knob for fixing the angular movement of said arm by said spring, an actuator switch positioned to be closed by forward movement of said arm upon rotation of said shaft by said clutch, an actuator electromagnet connected to be energized by closing of said actuator switch, a clutch-disengaging switch positioned to be closed by movement of said arm upon further rotation of said shaft, a clutch-disengaging electromagnet energizable by closing of said clutch-disengaging switch, a second clutch-disengaging switch operative to be opened by energization of said clutch-disengaging electromagnet, said second clutch-disengaging switch being operative upon being opened to deenergize said clutch-engaging electromagnet and disengage said clutch, a cam driven by a gear of said gearset operative to hold said second clutch-disengaging switch open after it has been opened until said arm has been returned to said stop by said spring, and means on said knob operative only when said knob is 50 in the off position to hold said motor switch open.
2. An instrument for electrically energizing the coil of an actuating device at selected accurately spaced intervals, which comprises, in combination, a constant speed electric motor, means for adjusting said motor for operation at different

speeds, a switch for starting and stopping said motor, a gearset drivably connected to said motor, a clutch shaft, a clutch engageable for drivably connecting said clutch shaft to the driven gear of said gearset, a clutch-engaging electromagnet, a switch operating arm extending radially from said clutch shaft operative to be turned forward by said clutch shaft when said clutch engages, a torsion spring for turning said arm backward when said clutch disengages, a graduated control knob rotatable forward from an off position, a stop carried on said control knob circumferentially movable by rotation of said knob for fixing the angular movement of said arm by said spring, an actuator switch positioned to be closed by forward movement of said arm upon rotation of said shaft by said clutch, an actuator electromagnet connected to be energized by closing of said actuator switch, a clutch-disengaging switch positioned to be closed by movement of said arm upon further rotation of said shaft, a clutch-disengaging electromagnet energizable by closing of said clutch-disengaging switch, a second clutch-disengaging switch operative to be opened by energization of said clutch-disengaging electromagnet, said second clutch-disengaging switch being operative upon being opened to deenergize said clutch-engaging electromagnet and disengage said clutch, a cam driven by a gear of said gearset operative to hold said second clutch-disengaging switch open until said arm has been returned to said stop by said spring, and means on said knob operative only when said knob is in the off position to hold said motor switch open.

3. An instrument for electrically energizing the coil of an actuating device at selected accurately spaced intervals, which comprises, in combination, a constant speed electric motor, a switch for starting and stopping said motor, a gearset drivably connected to said motor, a clutch shaft, a clutch engageable for drivably connecting said clutch shaft to the driven gear of said gearset, a clutch-engaging electromagnet, a switch operating arm extending radially from said clutch shaft operative to be turned forward by said clutch shaft when said clutch engages, a torsion spring for turning said arm backward when said clutch disengages, a graduated control knob rotatable forward from an off position, a stop carried on said control knob circumferentially movable by rotation of said knob for fixing the angular movement of said arm by said spring, an actuator switch positioned to be closed by forward movement of said arm upon rotation of said shaft by said clutch, an actuator electromagnet connected to be energized by closing of said actuator switch, a clutch-disengaging switch positioned to be closed by movement of said arm upon further rotation of said shaft, a clutch-disengaging electromagnet energizable by closing of said clutch-disengaging switch, a second clutch-disengaging switch operative to be opened by energization of said clutch-disengaging electromagnet, said second clutch-disengaging switch being operative upon being opened to deenergize said clutch-engaging electromagnet and disengage said clutch, a cam driven by a gear of said gearset operative to hold said second clutch-disengaging switch open until said arm has been returned to said stop by said spring, and means on said knob operative only when said knob is in the off position to hold said motor switch open.

4. An instrument for electrically energizing the coil of an actuating device at selected accurately

spaced intervals, which comprises, in combination, a constant speed electric motor, a switch for starting and stopping said motor, power transmitting means drivably connected to said motor, a clutch shaft, a clutch engageable for drivably connecting said clutch shaft to said power transmitting means, a clutch-engaging electromagnet, a switch operating arm extending radially from said clutch shaft operative to be turned forward by said clutch shaft when said clutch engages, a torsion spring for turning said arm backward when said clutch disengages, a graduated control knob rotatable forward from an off position, a stop carried on said control knob circumferentially movable by rotation of said knob for fixing the angular movement of said arm by said spring, an actuator switch positioned to be closed by forward movement of said arm upon rotation of said shaft by said clutch, an actuator electromagnet connected to be energized by closing of said actuator switch, a clutch-disengaging switch positioned to be closed by movement of said arm upon further rotation of said shaft, a clutch-disengaging electromagnet energizable by closing of said clutch-disengaging switch, a second clutch-disengaging switch operative to be opened by energization of said clutch-disengaging electromagnet, said second clutch-disengaging switch being operative upon being opened to deenergize said clutch-engaging electromagnet and disengage said clutch, a cam driven by said motor through said power transmitting means operative to hold said second clutch-disengaging switch open until said arm has been returned to said stop by said spring, and means on said knob operative only when said knob is in the off position to hold said motor switch open.

5. An intervalometer which comprises, in combination, a constant speed electric motor, a switch for starting and stopping said motor, power transmitting means drivably connected to said motor, a clutch shaft, a clutch engageable for drivably connecting said clutch shaft to said power transmitting means, a clutch-engaging electromagnet, a switch operating arm extending radially from said clutch shaft operative to be turned forward by said clutch shaft when said clutch engages, resilient means for turning said arm backward when said clutch disengages, a graduated control knob rotatable forward from an off position, a stop carried on said control knob circumferentially movable by rotation of said knob for fixing the angular movement of said arm by said resilient means, an actuator switch positioned to be closed by forward movement of said arm upon rotation of said shaft by said clutch for energizing an actuator electromagnet which is connected to be energized by closing of said actuator switch, a clutch-disengaging switch positioned to be closed by movement of said arm upon further rotation of said shaft, a clutch-disengaging electromagnet energizable by closing of said clutch-disengaging switch, a second clutch-disengaging switch operative to be opened by energization of said clutch-disengaging electromagnet, said second clutch-disengaging switch being operative upon being opened to deenergize said clutch-engaging electromagnet and disengage said clutch, a cam driven by said motor operative to hold said second clutch-disengaging switch open until said arm has been returned to said stop by said resilient means, and means on said knob operative only when said knob is in the off position to hold said motor switch open.

6. An intervalometer which comprises, in com-

bination, a constant speed electric motor, a switch for starting and stopping said motor, power transmitting means drivably connected to said motor, a clutch shaft, a clutch engageable for drivably connecting said clutch shaft to said power transmitting means, a clutch-engaging electromagnet, a switch operating means associated with said clutch shaft operative to be moved in a switch operating direction by said shaft when said clutch engages, resilient means for returning said switch operating means when said clutch disengages, a graduated control knob rotatable forward from an off position, a stop operated by said control knob movable by rotation of said knob for fixing the amount of movement of said operating means by said resilient means, an actuator switch positioned to be closed by movement of said switch operating means upon rotation of said shaft by said clutch for energizing an actuator electromagnet which is connected to be energized by closing of said actuator switch, a clutch disengaging switch positioned to be closed by movement of said switch operating means upon further rotation of said shaft, a clutch-disengaging electromagnet energizable by closing of said clutch-disengaging switch, a second clutch-disengaging switch operative to be opened by energization of said clutch-disengaging electromagnet, and second clutch-disengaging switch being operative upon being opened to deenergize said clutch-engaging electromagnet and disengage said clutch, a cam rotatably connected to said motor operative to hold said second clutch-disengaging switch open until said switch operating means has been returned to said stop by said resilient means, and means on said knob operative only when said knob is in the off position to hold said motor switch open.

7. In intervalometer which comprises, in combination, a constant speed electric motor, a switch for starting and stopping said motor, a clutch shaft, a clutch engageable for drivably connecting said clutch shaft to said motor, a clutch-engaging electromagnet, a switch operating means associated with said clutch shaft operative to be moved from a starting point in a switch operating direction by said shaft when said clutch engages, resilient means for returning said switch operating means to the starting point when said clutch disengages, a graduated control knob rotatable forward from an off position, a stop operated by said control knob movable by rotation of said knob for fixing the starting point of said switch operating means, an actuator switch positioned to be closed by movement of said switch operating means upon rotation of said shaft by said clutch for energizing an actuator electromagnet which is connected to be energized by closing of said actuator switch, a clutch-disengaging switch positioned to be closed by movement of said switch operating means upon further rotation of said shaft, a clutch-disengaging electromagnet energizable by closing of said clutch-disengaging switch, a second clutch-disengaging switch operative to be opened by energization of said clutch-disengaging electromagnet, said second clutch-disengaging switch being operative upon being opened to deenergize said clutch-engaging electromagnet and disengage said clutch, a motor driven cam operative to hold said second clutch-disengaging switch open until said switch operating means has been returned to said stop by said resilient means, and means on said knob operative only when said knob is in the off position to hold said motor switch open.

8. An intervalometer which comprises, in combination, a constant speed electric motor, a switch for starting and stopping said motor, a clutch shaft, a clutch engageable for drivably connecting said clutch shaft to said motor, a clutch-engaging electromagnet, a switch operating means associated with said clutch shaft operative to be moved from a starting point in a switch operating direction by said shaft when said clutch engages, means for returning said switch operating means to the starting point when said clutch disengages, a graduated control knob rotatable forward from an off position, a stop operated by said control knob movable by rotation of said knob for fixing the starting point of said switch operating means, an actuator switch positioned to be closed by movement of said switch operating means upon rotation of said shaft by said clutch for energizing an actuator electromagnet which is connected to be energized by closing of said actuator switch, a clutch-disengaging switch positioned to be closed by movement of said switch operating means upon further rotation of said shaft, a clutch-disengaging electromagnet energizable by closing of said clutch-disengaging switch, a second clutch-disengaging switch operative to be opened by energization of said clutch-disengaging electromagnet, said second clutch-disengaging switch being operative upon being opened to deenergize said clutch-engaging electromagnet and disengage said clutch, a motor driven cam operative to hold said second clutch-disengaging switch open until said switch operating means has been returned to said stop by said returning means, and means on said knob operative only when said knob is in the off position to hold said motor switch open.

9. An intervalometer for periodically actuating an electromagnetic device such as a camera shutter or the like, which comprises, in combination, an electric motor, means for starting said motor, a switch operating means, a clutch, engageable for drivably connecting said switch operating means to said motor, whereby said switch operating means is moved from a starting point in a switch operating direction when said clutch engages, a clutch-engaging electromagnet, means for returning said switch operating means to the starting point when said clutch disengages, a graduated control means movable away from an off position, a stop operated by said control means movable by movement of said control means for fixing the starting point of said switch operating means, an actuator switch positioned to be closed by movement of said switch operating means by said clutch and adapted to close a circuit through the electromagnet of said device, a clutch-disengaging switch positioned to be closed by further movement of said switch operating means, a clutch-disengaging electromagnet energizable by closing of said clutch-disengaging switch, a second clutch-disengaging switch operative to be opened by energization of said clutch-disengaging electromagnet, said second clutch-disengaging switch being operative upon being opened to deenergize said clutch-engaging electromagnet and disengage said clutch, a motor driven cam operative to hold said second clutch-disengaging switch open until said switch operating means has been returned to said stop by said returning means, and means on said control means operative only when said control means is in the off position to hold said motor starting means inoperative.

10. An intervalometer for periodically actuat-

ing an electromagnetic device, which comprises, in combination, an electric motor, means for starting said motor, a switch operating means, a clutch, engageable for drivably connecting said switch operating means to said motor, whereby said switch operating means is moved from a starting point in a switch operating direction when said clutch engages, a clutch-engaging electromagnet, means for returning said switch operating means to the starting point when said clutch disengages, a graduated control means movable away from an off position, means operated by said control means movable by movement of said control means for gauging the starting point of said switch operating means, an actuator switch positioned to be closed by movement of said switch operating means by said clutch and adapted to close a circuit through said device, a clutch-disengaging switch positioned to be closed by further movement of said switch operating means, a clutch-disengaging electromagnet energizable by closing of said clutch-disengaging switch, a second clutch-disengaging switch operative to be opened by energization of said clutch-disengaging electromagnet, said second clutch-disengaging switch being operative upon being opened to deenergize said clutch-engaging electromagnet and disengage said clutch, a motor driven cam operative to hold said second clutch-disengaging switch open until said switch operating means has been returned to said gauging means by said returning means, and means on said control means operative only when said control means is in the off position to hold said motor starting means inoperative.

11. An intervalometer for periodically energizing an electromagnet, which comprises, in combination, an electric motor, means for starting said motor, a switch operating means, a clutch, engageable for drivably connecting said switch operating means to said motor, whereby said switch operating means is moved from a starting point in a switch operating direction when said clutch engages, a clutch-engaging electromagnet, means for returning said switch operating means to the starting point when said clutch disengages, a control means movable away from an off position, means operated by said control means movable by movement of said control means for gauging the starting point of said switch operating means, an actuator switch positioned to be closed by movement of said switch operating means by said clutch and adapted to close a circuit through said electromagnet, a clutch-disengaging switch positioned to be closed by further movement of said switch operating means, a clutch-disengaging electromagnet energizable by closing of said clutch-disengaging switch, a second clutch-disengaging switch operative to be opened by energization of said clutch-disengaging electromagnet, said second clutch-disengaging switch being operative upon being opened to deenergize said clutch-engaging electromagnet and disengage said clutch, mechanism driven by said motor operative to hold said second clutch-disengaging switch open until said switch operating means has been returned to said gauging means by said returning means, and means on said control means operative only when said control means is in the off position to hold said motor starting means inoperative.

12. An intervalometer for periodically closing a circuit through an electric coil which comprises, in combination, an electric motor, a switch operating means, a clutch, engageable for drivably

- connecting said switch operating means to said motor, whereby said switch operating means is moved from a starting point in a switch operating direction when said clutch engages, a clutch-engaging electromagnet, means for returning said switch operating means to the starting point when said clutch disengages, a control means movable away from an off position, means operated by said control means movable by movement of said control means for gauging the starting point of said switch operating means, an actuator switch positioned to be closed by movement of said switch operating means by said clutch and adapted to close a circuit through said coil, a clutch-disengaging switch positioned to be closed by further movement of said switch operating means, a clutch-disengaging electromagnet energizable by closing of said clutch-disengaging switch, a second clutch-disengaging switch operative to be opened by energization of said clutch-disengaging electromagnet, said second clutch-disengaging switch being operative upon being opened to deenergize said clutch-engaging electromagnet and disengage said clutch, and mechanism driven by said motor operative to hold said second clutch-disengaging switch open until said switch operating means has been returned to said gauging means by said returning means.
13. An instrument for periodically closing an electric circuit, which comprises, in combination, an electric motor, a switch operating means, a clutch-engaging electromagnet, a clutch engageable by said electromagnet for drivably connecting said motor and said switch operating means to move said switch operating means to a switch operating position, means for returning said switch operating means to a starting position when said clutch disengages, a control means adjustable for selecting said starting position, an actuator switch positioned to be closed by movement of said switch operating means when actuated by said clutch and adapted to close said electric circuit, a clutch-disengaging switch positioned to be closed by additional movement of said switch operating means, a clutch-disengaging electromagnet energizable by closing of said clutch-disengaging switch, a second clutch-disengaging switch operative to be opened by energization of said clutch-disengaging magnet, and motor driven means operative to hold said second clutch-disengaging switch open until said switch operating means has returned to the selected starting point.
14. An instrument for periodically closing an electric circuit, which comprises, in combination, an electric motor, a switch operating means, a clutch-engaging electromagnet, a clutch engageable by said electromagnet for drivably connecting said motor and said switch operating means to move said switch operating means to a switch operating position, means for returning said switch operating means to a starting position when said clutch disengages, a control means adjustable for selecting said starting position, an actuator switch positioned to be operated by movement of said switch operating means when it is moved by said clutch and adapted to close said electric circuit, clutch-disengaging switch mechanism, adapted to be operated by additional movement of said switch operating means to break the circuit through said clutch-engaging electromagnet, and motor driven means operative to hold said clutch-disengaging switch mechanism in clutch-disengaging position until said

switch operating means has returned to the selected starting point.

15. An instrument for periodically closing an electric circuit, which comprises, in combination, a switch operating means, a clutch-engaging electromagnet, an electric motor operable independently of said clutch-engaging electromagnet, a clutch engageable by said electromagnet for drivably connecting said motor and said switch operating means to move said switch operating means to a switch operating position, means for returning said switch operating means to a starting position when said clutch disengages, a control means adjustable for selecting said starting position, an actuator switch for closing said electric circuit adapted to be operated by movement of said switch operating means by said clutch, clutch-disengaging switch mechanism also adapted to be operated by movement of said switch operating means by said clutch and operative to break the circuit through said clutch-engaging electromagnet without breaking the circuit through said motor, and mechanical means operative to hold said clutch-disengaging switch mechanism in clutch-disengaging position until said switch operating means has returned to the selected starting point.

16. An instrument for periodically closing an electric circuit, which comprises, in combination, a switch operating means, a clutch-engaging electromagnet, a power means operable independently of said clutch-engaging electromagnet, a clutch engageable by said electromagnet for drivably connecting said power source and said switch operating means to move said switch operating means to a switch operating position,

means for returning said switch operating means to a starting position when said clutch disengages, a control means adjustable for selecting said starting position, an actuator switch for closing said electric circuit adapted to be operated by movement of said switch operating means by said clutch, clutch-disengaging switch mechanism also adapted to be operated by movement of said switch operating means by said clutch and operative to break the circuit through said clutch-engaging electromagnet without affecting rotation of said power means, and means operative to hold said clutch-disengaging switch mechanism in clutch-disengaging position until said switch operating means has returned to the selected starting point.

17. An intervalometer comprising an interval measuring means, a prime mover, a clutch for connecting said interval measuring means to said prime mover to move said interval measuring means in interval measuring direction, said prime mover being operable independently of said interval measuring means when said clutch is disengaged, means to return said interval measuring means to a starting point, a control means for selecting said starting point, means operative by movement of said interval measuring means by said prime mover to actuate a camera shutter or the like, means also operative by movement of said interval measuring means by said prime mover to disengage said clutch without affecting operation of said prime mover, and means operative to hold said clutch disengaged until said interval measuring means has returned to the selected starting point.
